UNITED STATES PATENT OFFICE.

REED ADAMS, OF DETROIT, MICHIGAN.

PRINTING PRESS.

1,410,357.

Specification of Letters Patent. Patented Mar. 21, 1922.

Application filed July 10, 1919. Serial No. 309,795.

To all whom it may concern:

Be it known that I, REED ADAMS, a citizen of the United States, residing at Detroit, county of Wayne, State of Michigan, have 5 invented a certain new and useful Improvement in Printing Presses, and declare the following to be a full, clear, and exact description of the same, such as will enable others skilled in the art to which it pertains 10 to make and use the same, reference being had to the accompanying drawings, which form a part of this specification.

My invention relates to printing presses and an object of my improvement is to provide an improved process and apparatus for printing where the impression of the type is taken through a ribbon.

I secure this object in the apparatus illustrated in the accompanying drawings in 20 which:

Figure 1 is an elevation of a printing press embodying my invention.

Figure 2 is a plan view of the ribbon carrying frame detached from the press.

25 Figure 3 is an elevation partly in section of the parts adjacent to the printing surfaces.

Figure 4 is a detail plan view partly in section on the line IV—IV Fig. 1 to an enlarged scale looking in the direction of the arrow.

30 Figure 5 is a plan view of the frisket, or sheet for preventing improper distribution of the ink, with the parts extended into the same plane.

Figure 6 is a perspective view of the parts shown in Fig. 5 turned over upon itself as it is used in the press.

35 *a* is the movable platen of the press upon which the paper to receive the impression is placed. *c* is the form-bearing part having the form or type *c*² secured thereon. *b* is a frame carrying the inking ribbon. Said frame has an upper cross piece *b*³ and a lower cross piece *b*² and is pivoted in the manner of the frisket-bearing frame in the ordinary printing press. *d* *d* are rollers at the side of the frame upon which the inking ribbon *d*² is rolled, and is fed from one roller 40 to another.

45 *e* is the frisket, this consists of two folds which are substantially duplicates of each other, a single one being of the usual construction, that is to say, having apertures therethrough opposite the printing type. One of these folds is on the side of the ribbon 50

adjacent to the paper and prevents the discoloring of the paper by the ink in the spaces between the type. The other fold is upon the other side of the ribbon and prevents ink being deposited on the ribbon between the type as hereinafter described.

55 *f* is an ink distributing disk of the usual construction; and *g* *g* are the usual inking rollers. The ink is placed on the surface or 60 table in the usual way and is carried by the rollers *g* *g*, to the face of the type *c*² and is carried by the type to the adjacent side of the inking ribbon where the faces of the type come in contact with the ribbon, thus 65 a portion of the ink from the ribbon is carried to the paper in the usual way and the ink removed from the side of the ribbon adjacent to the paper is supplied by the type to the opposite side of the ribbon so that the 70 ink is never exhausted from the ribbon but is supplied at the same rate that it is used with the printing process, and is supplied directly opposite to where it is imparted to the paper. Thus the distribution of ink on 75 the ribbon remains uniform and the impression on the paper is not heavier in one place than another. To prevent the imparting of the ink to the portion of the ribbon from which it is not being removed the fold of 80 the frisket between the type and the ribbon is employed.

85 The frisket is folded over the cross bar *b*³ of the frame *b* at *e*⁴ and its lower edges *e*³ *e*³ are turned over the lower bar of said frame 90 and secured as shown in Fig. 3.

95 In the construction of the frisket I cut parallel slots adjacent and in line with one of the openings and turn up the material between said slots to form a loop *w* (Fig. 6) through which I insert a strip of the material of the paper *y* having barbs *y*² turned up therefrom. This strip is inserted from below as shown in Fig. 6 and covers a slot more or less as may be required, a barb *y*² 100 engaging the edge of the loop *w* to hold the strip in place.

105 What I claim is:

1. The combination in a printing press of a form-bearing and an impression surface, an inking ribbon between the form-bearing surface and impression surface, means for supplying ink to said form, and a frisket between said form-bearing surface and said ribbon.

110 2. The combination in a printing press of a form-bearing and an impression surface,

an inking ribbon between the form-bearing 5 surface and impression surface, and means for supplying ink to said form, and a frisket bent over the upper edge of said ribbon and having operative parts upon each side of the ribbon, substantially as and for the purpose described.

3. The combination in a printing press of a form-bearing and an impression surface, 10 an inking ribbon between the form-bearing surface and impression surface, means for supplying ink to said form, a frisket between said form-bearing surface and said ribbon and a frisket between said ribbon and said 15 impression surface.

4. A frisket provided with a loop, a strip 20 of sheet material extending through said loop and adapted to cover one of the openings in said frisket more or less according to the distance said strip is passed through said loop.

5. A frisket provided with a loop, a strip 25 of sheet material extending through said loop and adapted to cover one of the open-

ings in said frisket more or less according 25 to the distance said strip is passed through said loop, and barbs on said strip adapted to engage the surface of said loop for the purpose described.

6. A frisket provided with a loop, a strip 30 of sheet material extending through said loop and adapted to cover one of the openings in said frisket more or less according 35 to the distance said strip is passed through said loop, said loop being formed by turning up a portion of the material of the frisket.

7. A frisket provided with a loop, a strip 40 of sheet material extending through said loop and adapted to cover one of the openings in said frisket more or less according 45 to the distance said strip is passed through said loop, and barbs on said strip adapted to engage the surface of said loop, said barbs being formed of turned up portions of said strip.

In testimony whereof, I sign this specification.

REED ADAMS.
